UNITED STATES PATENT OFFICE.

JOHN J. HEYS, DECEASED, LATE OF LYNN, MASSACHUSETTS, BY LUCY A. HEYS AND GEORGE H. HEYS, EXECUTORS, OF LYNN, MASSACHUSETTS, ASSIGNEES TO UNITED SHOE MACHINERY CORPORATION, OF PATERSON, NEW JERSEY, A CORPORATION OF NEW JERSEY.

FORM LOCKING AND ADJUSTING DEVICE.

Application filed February 1, 1926. Serial No. 85,221.

The present invention relates to sole pressing machines and is herein illustrated as embodied in a so-called direct pressure leveling machine of the type disclosed in United States Letters Patent No. 881,478, granted March 10, 1908, on application of Benjamin F. Mayo.

Machines of this type are used for the purpose of leveling the sole of a shoe, that is, imparting to it the desired surface contour after previous shoemaking operations (such, for example, as the outsole stitching operation) have bent and otherwise disfigured the surface of the sole. In operation, the shoe is placed upon a so-called "last" which is an iron last-shaped shoe-support or jack located generally below a form which has a surface contour substantially the same as that which it is desired to impart to the sole of the shoe, and after bringing the shoe and form into proper registry, relative movement between the form and shoe is effected to cause the sole to be pressed between the form and the last, sufficient pressure being exerted to cause the sole to be smoothed out and to conform closely to the surface contour of the form.

It is the custom, for the sake of economy in operation, to use the same form for leveling the soles of shoes of a number of neighboring sizes. The surface of the form is made considerably larger than the sole of the largest shoe it is to treat, so that proper contact will be obtained under all conditions, but it is necessary that the ball line of the form correspond accurately to the ball line of each shoe treated and this requires that the machine provide for adjustment of the form longitudinally in order to bring the ball lines of shoes of different sizes into proper registration with the ball line of the form. For this purpose, in a well-known commercial embodiment of the type of machine illustrated in the above-mentioned Letters Patent, the form is secured adjustably to a form carrier which is locked in a fixed position on a form holder in the machine, and in order to effect the adjustment it is necessary to remove the form and its carrier from the form holder.

It is an object of this invention to provide improvements such as to facilitate adjustment of the form, with as little change as

possible in present commercial equipment. The invention has in view the provision of means including a form carrier of a different type from that heretofore in general use for securing the form on the form holder and for adjusting it without removing it from the machine. Since, however, it is the commercial practice to supply forms and carriers assembled as units to be mounted on the form holder of the machine, it is desirable that a manufacturer already supplied with one or more of such units be enabled to use them as well as units of the new type. The invention accordingly provides a construction such that form carriers of different types may be interchangeably secured to the form holder. In the construction shown the means for securing to the holder the earlier type of form carrier is left unchanged, and there is provided a device which may be readily attached to the holder for locking to the holder a form carrier equipped with more convenient means for adjusting the form. As herein illustrated such adjusting means comprises a screw on the carrier which abuts against the holder for adjusting the form and the carrier as a unit relatively to the holder, and the locking means comprises a member movable into or out of abutting engagement with the head of the screw. When the member is moved away from the head of the screw, the latter is readily accessible for effecting the adjustment while the form is in the machine.

The novel features of the invention, including various details of construction and combinations of parts, will now be more particularly described by reference to the accompanying drawings and pointed out in the claims.

In the drawings,

Fig. 1 is a plan view of a portion of a machine of the type illustrated in the above-mentioned Letters Patent, as modified for purposes of this invention;

Fig. 2 is a side elevation of the mechanism shown in Fig. 1;

Fig. 3 is a rear elevation of the mechanism shown in Fig. 1;

Fig. 4 is a plan showing the form assembled with a form carrier of the type shown in Figs. 1, 2 and 3; and

Fig. 5 shows a form carrier of the type commonly used heretofore.

As above stated, the illustrated machine is of the type set forth in United States Letters Patent No. 881,478, before referred to, to which Letters Patent reference may be made for a more complete disclosure of the construction and operation of parts of the machine not fully disclosed herein.

- 10 The block or cross-head 6 of the illustrated sole leveling machine has mounted upon its lower end a form holder 8 by means of co-operating segmental guide flanges 10 upon the block and corresponding 15 grooves 12 formed facing each other in up-standing lugs in the holder 8. This construction permits a slight longitudinal tipping movement of the holder 8 around the central axis of these segments, which is 20 limited by stop lugs 14 formed on the holder and slightly spaced from opposite sides of the block 6.

The form which engages the surface of the sole is indicated at 16. For purposes of 25 this invention a form carrier 18 (Figs. 1, 2, 3 and 4), in the shape of a strap dove-tailed in cross-section, is rigidly secured to the form by means of screws 20 and is adapted to be received in a supporting guideway 30 formed by correspondingly dove-tailed plates 22 secured upon the lower surface of the holder 8.

Adjustment of the form longitudinally to bring it into registration with the ball lines 35 of shoes of different sizes is effected, as herein disclosed, by sliding the form 16, and its attached carrier 18 along the plates 22, relatively to the form holder 8. To this end the forward extremity of the carrier 18 40 is bent upwardly at 24 to receive, in threaded engagement, a screw 26 and a lock nut, as shown.

The extremity of the screw 26 bears 45 against the forward part of the holder 8 and serves as an adjustable stop for the form to resist any tendency of the form, during the sole leveling operation, to move rearwardly. To resist any forward thrust of the form during the sole leveling operation a cylindrical projection or boss 28, (which will be further described below), located at the forward extremity of the form holder 8, is provided with a metal collar 30, detachably secured thereon by means of a 50 set-screw 32. Pivoted at the front of the collar 30 is a hooked arm 34, the extremity of which fits over the head of the screw 26 and acts as an abutment or locking device against which the head of the screw 26 55 presses when any forward thrust is imparted to the form 16. Obviously, the screw 26 will always fit between the members 8 and 34 irrespective of the adjustment of the member 24.

60 The form-adjusting means in use just

prior to the present invention is shown generally in United States Letters Patent No. 930,823, issued Aug. 10, 1909, on the application of E. E. Winkley. In this construction the dove-tailed form carrier 18^a was bent downwardly at its rear end, as shown in Fig. 5, and a set-screw 44 was provided in the down-turned portion to brace the form against any tendency to move backwards in operation and to assist in its adjustment as will be seen. The form itself was fastened to the strap or carrier by screws such as the illustrated screws 20 passing through slots 42 in the strap, and adjustment was secured by loosening the screws and sliding the form relatively to the strap. As stated above, such adjustment of the form required its removal from operative position in order to be able to get at the screws 20. The strap was locked relatively to the holder by a pin 38 (such as shown in Fig. 2), which slid up and down in a bored hole 36 in the cylindrical boss 28 above mentioned and entered a hole 40 in the form carrying strap 18^a.

It will be evident that when a machine is equipped with mechanism such as shown in Figs. 1 and 2 there may be utilized therein either a form to which is attached a form carrier such as shown at 18 in Fig. 4 or a form having thereon a form carrier such as shown at 18^a in Fig. 5. When the form is provided with the carrier 18, it is mounted in the machine in the manner illustrated in Fig. 2, the locking pin 38 being raised and resting idly upon the carrier. The form may then be readily adjusted while in position in the machine simply by turning the screw 26 while maintaining the inner end of the screw in engagement with the form holder 8, the locking member 34 being raised to afford access to the head of the screw. After the proper adjustment has been effected, the member 34 is returned to the position in which it is shown in Fig. 2, thereby serving as an abutment for locking the form against movement toward the left, while the screw in engagement with the holder prevents it from moving toward the right relatively to the holder 8. On the other hand, if a manufacturer should already have any forms equipped with carriers of the earlier type such as shown at 18^a in Fig. 5, he may readily use them by

100 mounting them in the machine in the same manner as illustrated in Letters Patent No. 930,823. In that case the pin 38 will be pushed into the opening 40 in the form carrier to lock the carrier in position, while the member 30 and its arm 34 remain idly in position on the form holder. It will be further evident that in order to utilize the advantages of the invention there is no necessity for altering the structure of a machine heretofore in use, but merely to

add to the old machine the locking attachment 30, 34 to co-operate with forms having thereon carriers such as shown at 18 in Fig. 4.

5 Having thus described the invention, what is claimed as new and desired to be secured by Letters Patent of the United States is:

10 1. In a sole leveling machine, a form holder adapted to support either of two kinds of form carriers, and a plurality of locking devices carried by the form holder, one of said locking devices being designed to co-operate with a form carrier of one 15 type, and the other of said locking devices being adapted to co-operate with a form carrier of the other type.

20 2. In a sole leveling machine, a form holder adapted to support either of two kinds of form carriers, and a plurality of locking devices carried by the form holder, one of said locking devices being designed to co-operate with a form carrier of one type, and the other of said locking devices 25 being adapted to co-operate with a form carrier of the other type, the latter locking device being supported by the former.

30 3. In a sole leveling machine, a form holder, a boss on the holder arranged to carry a pin for locking a form carrier to the holder, and a member detachably mounted on the boss constructed and arranged to co-operate with another type of 35 form carrier to lock it in position on the holder.

4. In a sole leveling machine, a form holder, a boss on the holder arranged to carry a pin for locking a form carrier to the holder, and a device detachably mounted

on the boss and comprising a member 40 pivoted to swing over the end of a different form carrier to lock it in position on the holder.

5. In a machine of the class described, a form holder, a device on said form holder 45 constructed to co-operate with one type of form carrier to secure a form in position on the holder, and another device on said form holder constructed to co-operate with a different type of form carrier provided with 50 a screw for adjusting the carrier and form as a unit relatively to the holder, said other device comprising a member movable into or out of locking engagement with the head of the screw.

55 6. In a machine of the class described, a form holder, a locking device on said form holder comprising a pin arranged to enter a recess in one type of form carrier to secure a form in position on the holder, and 60 another device detachably mounted on said form holder and constructed to co-operate with a different type of form carrier provided with a screw arranged to abut against the holder for adjusting the carrier and the 65 form relatively to the holder, said other device comprising a member mounted for swinging movement into or out of abutting engagement with the head of the screw for locking the carrier to the holder.

70 In testimony whereof we, the said LUCY A. HEYS and GEORGE H. HEYS, have signed our names to this specification.

GEORGE H. HEYS,

LUCY A. HEYS,

*Executors of the Will of John J. Heys,
Deceased.*
